A. A. GODFREY

MANUFACTURE OF LINOLEUM

Filed Nov. 22, 1923

INVENTOR

ALFRED ARTHUR GODFREY,

By his Attorneys,

Alfred Arthur Godfrey

UNITED STATES PATENT OFFICE.

ALFRED ARTHUR GODFREY, OF LONDON, ENGLAND, ASSIGNOR TO LINOLEUM MANUFACTURING COMPANY, LIMITED, OF LONDON, ENGLAND.

MANUFACTURE OF LINOLEUM.

Application filed November 22, 1923, Serial No. 676,321, and in Great Britain February 14, 1923.

The object of this invention is to produce linoleum which shall have the appearance of silver grain or figured oak or the like, that is, shall have in addition to the straight grain an additional grain or figures across the straight grain.

According to this invention such an effect is obtained by packing together a number of grained sheets or strips produced by any known method and having interleaved between them thin sheets or ribbons of linoleum material of the silver grain colour, that is, of the colour it is desired the cross grains above referred to should possess. These interleaved sheets or ribbons are preferably perforated, that is, have portions of irregular form cut out from them in order that the silver grain of the final product may be interrupted or broken up. These sheets or ribbons may be formed by painting or coating the surfaces of the sheets or strips with material of the colour required.

The assemblage of sheets is combined into a block which is then cut in planes perpendicular to the surfaces of the original sheets or strips and to the straight grain of those sheets or strips. The pieces thus cut may be of the thickness finally required but preferably the pieces so cut are considerably thicker than the final product is to be and are then rolled out to the required thickness.

The invention is illustrated by the accompanying drawing which is a perspective view showing part of the block referred to above.

A are grained sheets of linoleum material and B are thin sheets of linoleum material of the colour which it is desired the cross grains should possess. These sheets B have irregular holes C cut in them. It will be understood that though only six of each of the sheets A and B are shown a block in practice will usually contain many more such sheets. When the block has been thus formed it is subjected to pressure in the direction of the arrow D. After the block has been pressed it is cut in planes indicated by the lines E, that is, perpendicular to the surfaces of the sheets A and B and also to the straight grains of the sheets A. The pieces thus cut are then rolled out in the direction of the arrow F to the required thickness. The pressure applied to the block causes the sheets to be bent out of their original planes

in various ways and the material of the sheets B thus appears in wavy lines across the straight grain of the final product, giving the latter the appearance of figured oak or the like.

What I claim is:

1. The process for producing linoleum which consists in packing together a number of straight grained sheets of linoleum material alternating with thin sheets of material of a different colour so as to form a block and cutting the block thus formed in planes perpendicular to the surfaces of the original sheets in order to produce a plate having a continuous grain in one direction and another grain which crosses the straight grain at right angles.

2. The process for producing linoleum which consists in packing together a number of straight grained sheets of linoleum material alternating with thin sheets of material of a different colour so as to form a block, pressing the block so formed in a direction parallel to the planes dividing the sheets and at right angles to the grain of the first named sheets and cutting the pressed block in planes perpendicular to the surfaces of the original sheets and to the straight grain in order to produce a plate having a continuous grain in one direction and another grain which crosses the straight grain at right angles.

3. The process for producing linoleum which consists in packing together a number of straight grained sheets of linoleum material alternating with thin sheets of material of a different colour so as to form a block, pressing the block so formed in a direction parallel to the planes dividing the sheets and at right angles to the grain of the first named sheets, cutting the pressed block in planes perpendicular to the surfaces of the original sheets and to the straight grain and rolling the strips thus cut off in a direction at right angles to the surfaces of the original sheets in order to produce a plate having a continuous grain in one direction and another grain which crosses the straight grain at right angles.

4. The process for producing linoleum which consists in packing together a number of grained sheets of linoleum material alternating with thin perforated sheets of material of a different colour so as to form a

block and cutting the block thus formed in planes perpendicular to the surfaces of the original sheets.

5. The process for producing linoleum which consists in packing together a number of grained sheets of linoleum material alternating with thin perforated sheets of material of a different colour so as to form a block, pressing the block so formed in a direction parallel to the planes dividing the sheets and at right angles to the grain of the first named sheets and cutting the pressed block in planes perpendicular to the surfaces of the original sheets and to the straight grain.

6. The process for producing linoleum which consists in packing together a number of grained sheets of linoleum material alternating with thin perforated sheets of material of a different colour so as to form a block, pressing the block so formed in a direction parallel to the planes dividing the sheets and at right angles to the grain of the first named sheets, cutting the pressed block in planes perpendicular to the surfaces of the original sheets and to the straight grain and rolling the strips thus cut off in a direction at right angles to the surfaces of the original sheets.

7. The process for producing linoleum which consists in packing together a number of straight grained sheets of linoleum material alternating with thin sheets of material of a different colour so as to form a block, pressing the block so formed and cutting the pressed block in planes perpendicular to the surfaces of the original sheets and to the straight grain in order to produce a plate having a continuous grain in one direction and another grain which crosses the straight grain at right angles.

8. The process for producing linoleum which consists in packing together a number of straight grained sheets of linoleum material alternating with thin sheets of material of a different colour so as to form a block, pressing the block so formed, cutting the pressed block in planes perpendicular to the surfaces of the original sheets and to the straight grain and rolling the strips thus cut off in a direction at right angles to the surfaces of the original sheets in order to produce a plate having a continuous grain in one direction and another grain which crosses the straight grain at right angles.

9. The process for producing linoleum which consists in packing together a number of grained sheets of linoleum material alternating with thin perforated sheets of material of a different colour so as to form a block, pressing the block so formed and cutting the pressed block in planes perpendicular to the surfaces of the original sheets and to the straight grain.

10. The process for producing linoleum

which consists in packing together a number of grained sheets of linoleum material alternating with thin perforated sheets of material of a different colour so as to form a block, pressing the block so formed, cutting the pressed block in planes perpendicular to the surfaces of the original sheets and to the straight grain and rolling the strips thus cut off in a direction at right angles to the surfaces of the original sheets.

11. The process for producing linoleum which consists in packing together a number of grained sheets of linoleum material alternating with thin sheets of material of a different color and of less superficial area so as to form a block, and cutting the block thus formed in planes perpendicular to the surfaces of the original sheets.

12. The process for producing linoleum which consists in packing together a number of grained sheets of linoleum material alternating with thin sheets of material of a different color and of less superficial area so as to form a block, pressing the block so formed in a direction parallel to the planes dividing the sheets and at right angles to the grain of the first named sheets, and cutting the pressed block in planes perpendicular to the surfaces of the original sheets, and to the straight grain.

13. The process for producing linoleum which consists in packing together a number of grained sheets of linoleum material alternating with thin sheets of material of a different color and of less superficial area so as to form a block, pressing the block so formed and cutting the pressed block in planes perpendicular to the surfaces of the original sheets and to the straight grain.

14. The process for producing linoleum which consists in cementing together a series of pressed plates made of granulated and variously colored linoleum material, one upon the other to form a block and cutting strips from such composite block to produce grained sheets of linoleum material; packing together a number of such grained sheets alternating with thin sheets of material of a different color so as to form a block and cutting the block thus formed in planes perpendicular to the surfaces of the original sheets.

15. The process for producing linoleum which consists in cementing together a series of pressed plates made of granulated and variously colored linoleum material, one upon the other to form a block and cutting strips from such composite block to produce grained sheets of linoleum material; packing together a number of such grained sheets of linoleum material alternating with thin sheets of material of a different color so as to form a block, pressing the block so formed in a direction parallel to the plane dividing the sheets and at right angles to

the grain of the first named sheets and cutting the pressed block in planes perpendicular to the surfaces of the original sheets and to the straight grain.

- 5 16. The process of producing linoleum which consists in cementing together a series of pressed plates made of granulated and variously colored linoleum material, one upon the other to form a block and cutting
- 10 strips from such composite block to produce grained sheets of linoleum material; packing together a number of such grained sheets of linoleum material alternating with thin sheets of material of a different color

so as to form a block, pressing the block so ¹⁵ formed in a direction parallel to the planes dividing the sheets and at right angles to the grain of the first named sheets, cutting the pressed block in planes perpendicular to the surfaces of the original sheets and to ²⁰ the straight grain and rolling the strips thus cut off in a direction at right angles to the surfaces of the original sheets.

In testimony that I claim the foregoing as my invention I have signed my name ²⁵ this second day of November, 1923.

ALFRED ARTHUR GODFREY.
